UNITED STATES PATENT OFFICE.

FREDERICK W. MATHIEU, OF NEW YORK, N. Y., ASSIGNOR TO DUPLEXALITE CORPORATION, OF NEW YORK, N. Y., A CORPORATION OF NEW YORK.

LIGHTING FIXTURE.

Application filed December 4, 1918. Serial No. 265,202.

To all whom it may concern:

Be it known that I, FREDERICK W. MATHIEU, a citizen of the United States, a resident of the city of New York, county and State of New York, have invented an Improvement in Lighting Fixtures, of which the following is a specification.

My invention relates to lighting fixtures, and particularly such fixtures as are adapted to be used with electric incandescent or similar lamps. It is an object of the present invention to devise a fixture which shall be simple in construction and easy to manufacture, and one which may be readily assembled and disassembled. It is another object of the present invention to devise a fixture which will economically and agreeably distribute the light values of the source of light, to produce an effect which is pleasing to the eyes and to make highly economic use of the light values of the source of light employed.

By way of example, I have shown a preferred embodiment of the fixture of my invention in the accompanying drawings, wherein—

Fig. 1 is a side-elevation of such embodiment;

Fig. 2 is a cross-section partly in elevation of the same;

Fig. 3 is a bottom plan view of the same;

Fig. 4 is a detailed fragmentary view of a part of the same.

In the illustrative form here shown, the fixture comprises a cup-shaped member 1 with which is associated a tubular member 2 conducting the lead wires (not shown) to a lamp socket 3. Preferably the lamp socket 3 is provided with a flange member 4 attached thereto, as by being made integral with or by being soldered or otherwise attached to the same. Otherwise the lamp socket 3 may be of any usual or desired type of construction.

Associated with the lamp socket 3 are a plurality of, here shown as four supporting members 5. Each supporting member 5 preferably consisting of an integral wire, which may be of any desired cross-section, round or flat, here shown as flat, comprises a main portion 6, an inner bent portion 7 at one end of the main portion, and an outer portion 8 at the other end of said main portion. The outer portion 8 comprises a transversely

bent portion 9 having a hooked outer extremity 10. The bent portions 7 of the supporting members 5 are retained in the flange 4 of the socket 3 by such portions engaging apertures 11 in said flange.

Held in position by the hooked portions 10 of the supporting members 5 is a light distributing member 12, which preferably comprises a shallow member of spherical configuration. The member 12 is preferably translucent and is also provided on the inner side thereof with a highly reflecting surface 13.

Supported at the bends 14 between the main portions 6 and the transversely bent portions 9 of the supporting members 5 is a second light distributing member 15 comprising, preferably, an upwardly-flaring member which is translucent and is provided with an inner highly reflecting surface 16. The member 15 is preferably of a configuration which approximates the surface of revolution produced by revolving a portion of a parabola, as more clearly seen in Fig. 2 of the drawings.

While various materials, opaque, translucent, or transparent, and made of metal, glass, porcelain, or fabric may be employed for the members 12 and 15, I prefer, as already described, to make these members of translucent material having inner highly reflecting surfaces. For this purpose I prefer to use composite-layer vitreous material, clearly shown in section in Fig. 4 of the drawings, and consisting of an outer layer 17 of opal or other translucent glass, an inner layer 18 of highly polished, highly reflecting, ordinary transparent glass, having a reflecting index or albedo approaching that of the ordinary silvered mirror, and an intermediate layer 19 of a glass which is intended to remove or dissipate the undesirable, such as the ultra-violet, components of the source of light, thereby rendering the light soft and agreeable to the eyes.

The manner of assembling the fixture of my invention will be substantially clear from the foregoing description. After removing the fixture as a whole from the ceiling or other structure to which the same is attached, the member 15 may be removed, after which the member 12 may be removed. The supporting members 5 are readily detach-

able, and after detaching the same, the lamp 20 may be removed from the socket 3.

By the arrangement and disposition of the members 12 and 15, and by reason of the 5 translucent and light reflecting properties of the same, I am enabled to produce a lamp of highly desirable properties which economically and agreeably distributes the light values of the source of light and produces a 10 very pleasant and attractive light. The members 12 and 15 are so arranged that some light reflected from the surface 13 of member 12 will be received by the outer surface 21 of the member 15, the outer surfaces of 15 both members 12 and 15 being sufficiently reflecting to help distribute any light received by them by reflection.

It is, of course, to be understood that my invention is not to be limited to the specific 20 embodiment thereof, here shown and described by way of example merely.

What I claim is:

In an electric lighting fixture, the combination of a lamp and socket, a socket cover having an outwardly extending flange, a 25 plurality of supporting rods associated with said socket, such rods having upper ends retained in said flange and flaring portions comprising an outwardly extending transverse portion having hooked extremities, a spherical translucent member retained and supported by said hooked portions and an upwardly flaring member of translucent material open top and bottom surrounding the rods and supported 30 below the lamp filament of said transverse portions.

In testimony whereof, I have signed my name to this specification this 30th day of November, 1918.

FREDERICK W. MATHIEU.
